UNITED STATES PATENT OFFICE.

GEORGE WILKINSON, OF PROVIDENCE, RHODE ISLAND, ASSIGNOR TO JOHN P. ADAMS, OF BROOKLYN, NEW YORK.

DESIGN FOR AN ICE-PITCHER BODY.

Specification forming part of Design No. 5,284, dated September 26, 1871.

To all whom it may concern:

Be it known that I, GEORGE WILKINSON, of the city and county of Providence and State of Rhode Island, have invented and produced a new and original Design for an Ice-Pitcher Body, of which the following is a specification, of which the accompanying drawing forms a part.

The nature of my said design is fully represented in the accompanying drawing, and consists of an ice-pitcher body, B, the outline of which is cylindrically straight from top to bottom.

I do not herein claim the said design for vessels other than ice-pitchers.

I claim as my invention—

The design for an ice-pitcher body, as shown and described.

Witnesses: GEORGE WILKINSON.

ISAAC A. BROWNELL,

THEODORE A. BARTON.
